UNITED STATES PATENT OFFICE

2,506,759

SCRAPER AND LOADER

Edwin Wommer, Bayfield, Colo., assignor of one-half to Emil Arndt, La Plata County, Colo.

Application October 13, 1947, Serial No. 779,624

5 Claims. (Cl. 37—124)

1

This invention relates to a combined scraper and loader attachment designed for use in connection with tractors, and aims to improve generally the construction as set forth in my Patent Number 2,341,007 dated February 8, 1944.

An important object of the invention is to provide operating means including a push bar whereby the side swing of the scoop is controlled.

Another important object of the invention is to provide an operating means including a scoop stop which is so designed as to let the scoop dump completely by movement of the scoop to a vertical position.

Still another important object of the invention is to provide yieldable means for returning the scoop to its normal position after operation, thereby eliminating the necessity of manually controlled means for returning the scoop.

A further object of the invention is the provision of means in the form of a disk which constitutes a part of the scoop support, which disk operates to maintain the scoop level, preventing it from tipping sideways while in operation.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Figure 1 is a side elevational view of a scraper and loader, constructed in accordance with the invention.

Figure 2 is a plan view thereof.

Figure 3 is a plan view of the scraper and loader, and illustrating the scoop and supporting arm as swung laterally of the line of advance of the machine.

Figure 4 is a sectional view taken on line 4—4 of Figure 2.

Figure 5 is a sectional view taken on line 5—5 of Figure 3.

Referring to the drawings in detail, the attachment comprises a platform indicated generally by reference character 5, which platform includes a forward transverse bar 6 which is secured to the pivoted side rails 8 of the conventional hydraulic implement lift frame of a tractor.

Mounted on the platform 5, is the turntable 9 which is provided with stops 10 extending from the edge thereof, the stops 10 being arranged to engage the pins 11 that extend upwardly from the

platform 5 when the turntable is rotated in one direction, thereby restricting movement of the turntable and beam which is connected therewith, and which supports the scoop, to be hereinafter more fully described.

The scoop beam includes an inner section 12 and a telescopic outer section 13, the outer section 13 providing that section of the beam to which the scoop is connected.

10 The reference character 14 indicates a supporting disk which has pivotal connection with the section 13 of the beam at 15, to which disk the swivel bar 16 is connected, the bar 16 having pins 17 at its ends that are fitted in openings formed in the scoop arms 18' that rise from the scoop, and are secured to the sides of the scoop.

The scoop, which is indicated by the reference character 18', is rotated with respect to its supporting beam by means of the control rod 18 which embodies telescoping sections, one section of the rod being connected to the swivel bar 16 at 19, the opposite end of the control rod receiving the telescoping section 20, which has pivotal connection with the pivoted cross arm 21, at 22.

20 The cross arm has a pivotal connection with the section 12 of the main supporting beam at 23. A link 24 has a pivotal connection with one end of the cross arm 21 at 21', and has its opposite end pivotally connected with the plate 25, at 26.

This plate 25 has downwardly disposed extensions 7' that have right-angled ends 7, secured to the side rails 8 by the U-bolts 9'.

Carried by the inner end of the section 12 of the supporting beam is a roller 25' that bears against the under surface of the plate 25 providing a bearing for the beam.

Extending laterally from the supporting beam and secured thereto is an arm 27 to which the end 28 of the connecting rod 29 is connected, the connecting rod being telescopingly arranged within the end 28.

45 A coiled spring 30 has one of its ends connected to the end 28, while the opposite end of the coil spring is connected to the inner section of the connecting rod 29, at 31. Thus it will be seen that when the main beam has been moved to the position as shown by Figure 3 of the drawings, and the operating mechanism released, the coiled spring will act to return the main beam and scoop supported thereby, to the position as shown by Figure 2 of the drawings.

It might be further stated that at one end of the rod 29 is an eye 32 connected to one of the fenders of the tractor, by means of the U-bolt 33.

Adjustably supported within the scoop 18' is

a guard 34 which guard is formed with an elongated opening in which the bolts 35 extend, the bolts also passing through openings in the rear wall of the scoop. This guard is designed to be engaged by the scoop beam 13 when the scoop tilts to a digging position, and the rear end of the scoop is tilted upwardly thereby restricting pivotal movement of the scoop to insure the scoop assuming the proper digging or scooping position.

Connected with the arm 36 that is secured to the rear end of the scoop by means of the bolt 35, is the dump cable 37 which extends to a point adjacent to the operator's seat, so that the operator may have easy control over the dumping of the scoop, which is accomplished by pulling the dump cable when the scoop has been moved to the proper dumping position.

Connected with the usual power lifting arms 38 of the hydraulic implement lift of the tractor, are the links 39 that connect with the side rails 8, with the result that when the arms 38 are pulled upwardly by the power arms 38, the turntable is caused to rotate, swinging the main beam laterally so that the loaded scoop 18' can be dumped at one side of the excavation.

The swinging of the main beam laterally is caused by the shortening of the horizontal distance between the pivot 26 and the pivot 24, as the main beam is elevated.

Since the arms 38 and links 39 remain in the position as shown by Fig. 2, until they are actuated by the power of the tractor, the scoop will naturally be held in a cutting path parallel to the path of travel of the tractor.

In view of the foregoing detailed description, it is believed that a further description as to the construction and operation of the attachment is unnecessary for a clear understanding of the invention.

Having thus described the invention, what is claimed is:

1. A scraper and loader attachment for tractors, comprising a platform adapted for positioning on the side rails of a tractor, a turntable mounted on the platform, stops mounted on the turntable and extending from the periphery thereof, pins rising from the platform and being disposed in the paths of travel of the stops restricting movement of the table on the platform, a telescoping scoop supporting beam secured to the turntable, and means for pivotally mounting a scoop at the free end of the scoop supporting beam, and means for rotating the turntable operating the supporting beam and scoop.

2. A scraper and loader attachment for tractors, comprising a platform, means for securing the platform to the side rails of a tractor, a turntable mounted for rotary movement in a horizontal plane mounted on the platform, stops

5 mounted on the platform and engaging the turntable restricting rotary movement of the turntable, a telescoping scoop supporting beam secured to the turntable, a disk mounted at the outer end of the beam, a swivel bar mounted for rotation under the disk, means for pivotally connecting a scoop to the bar, and means for rotating the turntable operating the beam and scoop.

10 3. A scraper and loader attachment for tractors, comprising a platform, means for securing the platform to the chassis of a tractor, a turntable mounted on the platform, a scoop supporting beam secured to the turntable, a swivel bar pivotally mounted at the outer end of the supporting beam, a scoop swivelled to the bar, a cross arm pivotally connected to the beam, a link connected with one end of the cross arm, the opposite end of the link being pivotally connected to the platform, a control rod connected with the opposite end of the cross arm, said control rod being also pivotally connected to the bar, whereby swinging movement of the beam rotates the bar and scoop mounted thereon, and means for moving the scoop supporting beam.

15 4. A scraper and loader attachment for tractors, comprising a platform, means for securing the platform to the side rails of a tractor chassis, a turntable mounted on the platform, a plate connected with the chassis and disposed above the turntable, a scoop supporting beam secured to the turntable, the scoop including a swivel bar, pivotally connected to the outer end of the beam, means including a cross arm, a link and control rod, connecting the plate with the scoop whereby movement of the beam results in a rotary movement of the scoop, and means for swinging the turntable and scoop supporting beam in a horizontal plane.

20 5. A scraper and loader attachment for tractors, comprising a platform, means for attaching the platform to a tractor chassis, a turntable mounted on the platform, a telescoping supporting beam secured to the turntable, a scoop pivotally mounted on the outer end of the beam and adapted to pivot vertically and horizontally, means for swinging the scoop in a horizontal plane, means for pivoting the scoop vertically, and means for automatically returning the scoop and beam to its normal position.

EDWIN WOMMER.
